US00D630358S

(12) **United States Design Patent**
Nelson et al.

(10) **Patent No.:** US D630,358 S
(45) **Date of Patent:** ** Jan. 4, 2011

(54) **ILLUMINATING DEVICE**

(75) Inventors: **David Nelson**, Las Vegas, NV (US);
Wai-Ming Law, Yuen Long (HK)

(73) Assignee: **SOL-Light, LLC.**, Las Vegas, NV (US)

(**) Term: **14 Years**

(21) Appl. No.: **29/353,181**

(22) Filed: **Jan. 4, 2010**

(51) **LOC (9) Cl.** **26-05**

(52) **U.S. Cl.** **D26/60; D26/61**

(58) **Field of Classification Search** D26/60-66,
D26/37, 38, 40, 43, 44, 46, 51, 104, 47, 52;
362/98, 99, 157, 174, 800, 191, 197, 198,

(57) **CLAIM**

The ornamental design for an illuminating device, as shown and described.

DESCRIPTION

FIG. 1 is a perspective view of an illuminating device showing our new design;

FIG. 2 is a left side view thereof;

FIG. 3 is a right side view thereof;

FIG. 4 is a front view thereof;

FIG. 5 is a rear view thereof;

FIG. 6 is a bottom view thereof; and,

FIG. 7 is a top view thereof.

The broken line showing of the circular lens and the remainder of the illumination device is for illustrative purposes only and forms no part of the claimed design.

1 Claim, 4 Drawing Sheets
